HEATING DEVICE

Walter L. Mayne, Cincinnati, Ohio

Application October 3, 1938, Serial No. 232,951

8 Claims. (Cl. 257—136)

The present invention relates to heating devices and has for an object the provision of a room heater which is constructed of sheet metal and in which all heating surfaces are prime heating surfaces.

Another object of the invention is to provide a heater in the nature of radiator for warm water, vapor, or steam heating systems, wherein the front of the room heater provides a source of radiant heat at all times while the remaining heating sections of the device are operative as convector heaters and only at such intervals as are necessary to supply a demand for heat.

A further object of the invention is to provide heaters of the type referred to and wherein the pressure of thermal circulation is effective at all times through the front portion of the heater and wherein a pump or forced circulator operated by means under the control of a room thermostat serves to supply forced circulation through the convector portion of the heaters without the necessity for mechanical operation of valves or other mechanism.

A further object of the invention is to provide a heater of the class described wherein a hollow front panel serves, at the same time, as a source of predominately radiant heat and a cover and closure for the heater element.

A still further object of the invention is to provide a heater of the class described which is adapted for partial or complete recessed wall mounting as well as a free-standing heating unit.

Still another object of the invention is to provide a heating unit employing media such as warm water, vapor or steam with a hollow front panel for constant radiant heat and a series of convector units concealed thereby and an orificed header tube in constant communication with said panel and convector units and so designed that thermal circulation occurs in the hollow panel and not in the convector and when forced circulation is rendered operative in the supply line, the convector units are automatically supplied with circulating heat medium in order that the room air may be heated by convection.

These and other objects are attained by the means described herein and disclosed in the accompanying drawings, in which:

Fig. 1 is a perspective view of an encased heater embodying the invention, parts being broken away.

Fig. 2 is a view taken on line 2—2 of Fig. 1.

Fig. 3 is a view taken on line 3—3 of Fig. 1.

Fig. 4 is a view taken on line 4—4 of Fig. 1.

Fig. 5 is a perspective view of an orificed tube forming a detail of the invention.

Fig. 6 is a view taken on line 6—6 of Fig. 5.

Fig. 7 is a view taken on line 7—7 of Fig. 5.

The present day trend in the direction of the disposition of heaters, and particularly radiators in wall recesses has become firmly established. The disposition of radiators of the old known type behind a grille or closing panel results in nearly a complete loss of the predominately radiant heat from such devices and the tendency to offset the loss in efficiency by increased area is in itself an extravagance and it furthermore contributes to the inconvenience and discomfort experienced by the well-known heat over-run alternated with a sense of excessive cooling which is experienced with the present day completely automatic heating systems. The present invention seeks to obviate the disadvantages just enumerated and to provide practically perfect operation under all conditions during the heating season, utilizing, for the accomplishment of this, relatively inexpensive sheet metal room heating devices and an appreciably simplified automatic heating plant. The heating devices are so constructed with a self contained supply column and adjustable supply header that they function at increased efficiency as ordinary radiators in a system which is not automatic.

Referring now to the drawings and particularly Figs. 1 and 2, the heating unit of the invention comprises a suitably constructed sheet metal casing including a top wall 15, end walls 16, rear wall 17, and a hollow panel indicated generally as 18 and which partially closes the front of the casing. The hollow front wall 18 is formed by a front sheet 19 and a rear sheet 20 each having, in its upper part, a rectangular opening. The edges of said openings are connected to the edges of a bounding wall 21, the vertical portions of which are provided with apertures receiving the opposite ends of a plurality of spaced apart tubes 22 which form a grille for the air outlet aperture 23 which is bounded by said wall 21. The front sheet 19 of hollow panel 18 is extended downwardly to the floor level as at 24 and connects with the opposite side walls 16 of the casing. The bottom wall 25 of hollow panel 18 closes the space between sheets 19 and 20 which are otherwise closed by top wall 15 and end walls 16. From the foregoing, and as shown in Fig. 3, it will be seen that walls 19 and 20 form a top horizontal flow channel 26 above aperture 23 and another flow channel 27 below said aperture. 55 The material of sheets 19 and 20 is corrugated

or formed by bringing together the sheets at suitable intervals and welding them or otherwise securing them as at 28 thus forming between them a series of vertical flow tubes 29 which communicate at their tops with channel 27 and at their bottoms with still another horizontal flow channel 30.

As shown in dotted lines in Fig. 1 a supply column is formed integrally within the hollow panel 18 by providing an interior wall 31 which forms substantially a continuation of the left-hand vertical portion of wall 21, this wall 31 being continued below the level of bottom wall 25 of panel 18. The back sheet 20 of the panel is likewise continued for a distance below the bottom wall 25 and which, together with end wall 16, front wall portion 24 and the inserted wall 31, form a closed bottom for the supply column. This projecting portion of the supply column has a suitable elbow welded thereto to which a shut-off valve 32 communicating with supply pipe 70 is connected. The top of the supply column is closed by a small inserted piece 33 having a small orifice 34 which establishes communication between the vertical supply column and the top horizontal flow channel 26. Pipes 22 provide communication between the supply column and the vertical right hand flow channel of the front hollow panel 18. A baffle plate 35 extends diagonally across the said vertical flow channel and its purpose is to direct descending fluids horizontally across flow channel 27 so that the fluids may descend through the vertical tubes or ways 29 formed by the corrugations in the hollow panel. A return header 36 communicating with discharge pipe 72 has a piped connection 37 in the bottom wall 25 of the hollow panel. Parallel to and disposed behind the front panel 18 are convective units 38 which are welded or otherwise secured to the return header 36 and which have outlets 360 communicating with said return header. The convective units may be of any suitable number depending upon the size and capacity desired in the particular heating unit. In the present illustration the convective units are three in number. As can be readily seen at the right hand side of Fig. 1, the convective units are of a height substantially equaling the lower continuous panel portion of the front closing panel portion 18, i. e., they are generally similar save for the upper aperture and its framing in the front panel 18. These convective units 38 each have an upper-flow channel 39 corresponding to the flow channel 27 of the front panel, and a lower horizontal flow channel 40, corresponding to the bottom flow channel 30 of said front panel. At the left hand side of the heating unit is a horizontal supply header indicated generally at 41 and which is shown in enlarged detail in Fig. 5. This supply header provides constant communication between the interior of the supply column and the inside of said supply header and the convective units 38 have constant communication therewith. The horizontal supply header is so designed as to provide unrestricted communication between it and the supply column and to enable the selective adjustment of the header from the exterior of the heating device in order to provide selected sizes of restricted communicating orifices between the respective convective units and said supply header. This is accomplished in the following manner. The supply header 41 is made up of an outer tube 42 which has a relatively large orifice 43 at points along the

bottom thereof surrounding which orifices the several convective units have a welded connection. Rotatably adjustable within the outer tube 41 is an inner tube 44 which has an annular series of orifices 45, 46, 47 and 48 each of a different diameter and any one of which in a given series may be brought into registry with a corresponding orifice 43 in the outer header tube 42 by rotatable adjustment of the inner tube (see Fig. 7). The portions of the tubes 42 and 44 which traverse the vertical supply column have enlarged slots 49 and 50 which are so proportioned that the free flow of fluid from the supply column into the supply header and also into the top of said supply column can never be materially restricted. The inner tube 44 has an angular protruding head 51 with slots 52 and 53 crossing each other and forming indicators for the location of the lines of perforations on the inner tube. By adjusting head 51 angularly to dispose a selected slot, indexed as A, B, C or D to a downward vertical direction, the installer will know that he has disposed the selected row of perforations 45, 46, 47 or 48 in registry with the orifices 43. The tubes comprising the horizontal supply header are fixed in the heater and held in adjusted position by means of lock nuts 54 and 55 together with suitable packing. Preferably the outer tube of the supply header has a washer 56 welded thereon in order to simplify the welding thereof to the hollow panel.

In the operation of the heating unit of the invention as an ordinary radiator, i. e., when the heaters are connected in an ordinary warm water, steam, or vapor system, the adjustable supply header would be adjusted to bring the largest orifices 48 into registry with the orifices 43 so that a full flow of the heating medium would take place through both the hollow front panel 18 and through each of the convective units 38. The thermal flow of the heating medium is as follows: The heating medium flows upward through the supply column and into the top cross flow channel 26 by way of orifice 34 of the hollow panel and across to the right-hand side thereof. At the same time the heating medium flows through the several pipes or tubes 22 which span the opening 23 in the panel and this heating medium also empties into the right hand side of the hollow panel. The heating medium then descends to the level of cross flow channel 27 and it is directed in a substantially horizontal flow by the baffle 35. The heat medium then descends through the vertical tubes 29 and into the bottom horizontal channel 30 from which it flows in the opposite direction through the outlet pipe 37 into the return header 36. At the same time the supply header 41 delivers heating medium into the top left hand end of each of the convective units 38 and the heating medium flows across and down through the vertical tubes of the convective units to the bottom horizontal channels 40 thereof from whence it flows out through return header 36. It should be here noted that the convective units 38 function essentially to heat the air of the room by convection, and that the air to be heated enters through the bottom opening or aperture of the front panel and wipes or scrubs over the prime heating surfaces presented by the rear face of the closure panel 18 and the front and rear faces of each of the convective units 38 and is discharged through the spaces between the tubes 22 in the upper aperture 23 of the front panel. The tubes, forming the grille in aperture 23, are of themselves also

prime heating surfaces and are particularly effective in quickly inducing the air flow through the device. The term "prime heating surfaces" is herein used to denote surfaces of metal which are directly contacted on one face by the heating medium. The devices of the invention comprise substantially all prime heating surfaces and substantially no "extended" surfaces, such as fins or other metal areas which receive heat by conduction along the metal before exposure to the air.

General operation of the heating device of the invention in a so-called "automatic" heating system will now be described with a generalized reference to the functions of the system, following which the heating units in connection with simplified automatic heating systems will be described.

An automatic heating system for warm water, steam or vapor heating systems includes essentially an automatic firing device, e. g., a coal stoker, gas burners or oil burners, etc., governed by automatic devices such as aquastats or pressurestats in such fashion as to maintain an adequate supply of the heating medium at all times. Such systems also include means under the control of a room thermostat to provide increased rate of circulation of the heating medium by forced circulation with a pump, in the case of a warm water heating system or by the automatic adjustment of pressure control valves in the case of steam or vapor heating systems.

The heating devices of the invention, when utilized in automatic systems, as hereinbefore referred to, will be initially adjusted by turning the angular head 51 of the horizontal supply header 41 to effect registry of one of the series of smaller orifices 47, 46, or 45 in inner tube 44 with the series of orifices 43 in the outer tube 42. The series of orifices selected would be such that the pressure due to the operation of the water pump or the higher pressure supplied by automatic control valves of the system will drive the heating medium through the restricted orifices, while the lesser pressure in the system, viz., when the pump is at rest or the high pressure controls are shut off, is insufficient to pass the heating medium through the restricted orifices. At all times, however, any gravity flow or thermal circulation of the heating medium will readily flow through the channels and tubes of the panel 18 by way of the supply column because the enlarged slots 49 and 50 of the outer and inner tubes of the supply header offer no resistance to thermal circulation at the intersection of the supply column and the supply header in front panel 18. The enclosing panel 18 and its concealing grille tubes 22 will therefore at all times constitute prime heating surfaces sending out essentially radiant heat into the room, and afford the occupants of the room a sense of comfortable warmth. This supplies sufficient heat to the room in milder seasons to maintain the temperature for which the room thermostat is set.

The arrangement and functioning hereinbefore described affords an opportunity to provide adequate heat and comfort in a most efficient and economical fashion and particularly does it avoid the objectionable occurrence of alternate heat over-runs and periods of perceptible chilling in the room.

The electrical circuit in Fig. 9 consists of a "hot side" supply line 28 which connects to one terminal of low pressurestat 78 and to conductor 89 which connects to one side of room thermostat 79 which is of line voltage type. Firing de-

vice 76 is connected to the remaining terminal of pressurestat 78 by conductor 90. The remaining terminal of the firing device 76 is connected to return supply line 91. High pressurestat 77 has one terminal connected to room thermostat 79 by conductor 92, and the other terminal is connected to the firing device by conductors 93-90. The operation of the high and low pressurestats will be understood readily. The thermostat closes on heat demand in the room, and the firing device operates under the control of high pressurestat 77. When the room temperature demand is satisfied the thermostat breaks the circuit and the firing device operates to maintain a suitable low pressure under the control of pressurestat 78.

It will be understood that the adjustment of the supply header tube orifices is provided in order to enable the installing contractor to initially adapt each heating device to the particular system and duty imposed upon it so that identical structures may be utilized to serve a variety of requirements in a number of different systems employing fluid heating media. After being once properly adjusted in the system there is no further need for changing the orifice setting in the supply header.

At the top of the front face of the hollow closure panel a tapped hole T is provided into which a suitable venting valve (not shown) is inserted. This arrangement permits the convector units as well as the hollow radiator panel to be relieved of any entrapped air because the air can pass through the top of the convector units, through the supply header and upwardly through the supply column into the top of the panel.

While the devices of the invention are of exceptionally high efficiency because of the automatic self-accommodation to heat demands in a particular system, it will be understood that the selective modification of the output of predominately radiant heat or combined radiant and convected heat may be attained through the manual control of the boiler output pressures in the system.

While the heating units of the invention are, by preference, formed of sheet metal in order to reduce the ratio of heat output to metal poundage, the devices are not limited to the particular construction herein described. The devices may be otherwise constructed, for example, they may embody predominately cast metal construction particularly if space and design are of no vital consequence.

55 What is claimed is:

1. A heating unit comprising a front hollow closed panel including means to space the base thereof from a flow surface and having a warm air outlet aperture adjacent the top, the body of the panel intermediate said aperture and said base being corrugated to form vertical passages and communicating horizontal top and bottom transverse flow channels, a wall disposed internally of said hollow panel at one side of said corrugations and forming a supply column, tubular members spanning the aperture in the panel and providing communication between said column and the opposite side of said panel, and a baffle in the panel on the side opposite said supply column and below the aperture.

2. A heating unit comprising a hollow panel adapted to serve as a closure for a wall recess, a plurality of convector units disposed in spaced parallel relation behind said hollow panel, a sup-

ply header having open and free communication with the upper part of said hollow panel and further having restricted communication with each of said convactor units, said supply header connectible to a source of fluid-heating medium, the hollow panel receiving a circulating supply of fluid heating medium under substantially all conditions of its connected source, said convactor units being inoperative when the pressure of the source is insufficient to pass the fluid heating medium through the restricted communication from the supply header.

3. A room heater for mounting in a wall recess comprising a metallic casing, a hollow closure panel forming the front of said casing and having an upper aperture, a vertical supply column formed at one side of said panel the bottom of said panel being spaced from the bottom of said casing, a tubular supply header projecting through said panel in communicating relation with the supply column and having restricted orifices in spaced-apart relation within the casing, and convactor units disposed in the casing behind said panel and communicating at one end thereof with said restricted orifices, and a return header in open communication with the opposite ends of said convactor units and said panel.

4. The combination with a radiator and convactor heater of a supply distributor therefor comprising a tubular member closed at one end and having a series of aligned perforations in the wall thereof, a second tubular member rotatable within the first-mentioned member and having annular series of spaced orifices of graduated size registerable with the perforations in said tubular casing upon rotation of the inner tubular member relative to said casing, said tubular members provided adjacent one end with a plurality of enlarged openings in constant and uncontrolled registry and affording unimpeded fluid flow diametrically across the interior of said end of the distributor in all positions of said second tubular member said enlarged openings affording communication with the radiator, said orifices of graduated size controlling communication with the respective portions of the convactor.

5. A space heating device comprising a hollow panel having a self-contained vertical supply column at one side thereof, a horizontal supply header traversing said column near the top and communicating therewith, hollow convactor units arranged behind the panel in spaced relation and having communicating connection at their tops with the said supply header, and a return header

connecting with said panel and said convactor units at the bottom thereof.

6. A space heating device comprising a hollow panel having a self-contained vertical supply column at one side thereof, and a vent tap opening at the other side at the top thereof, a horizontal supply header traversing said column near the top and communicating therewith, hollow convactor units arranged behind the panel in spaced relation and having communicating connection at their tops with the said supply header, and a return header connecting with said panel and said convactor units at the bottom thereof, the vent tap opening in the panel adapted for the reception of a venting valve whereby the convactors and panel may be vented.

7. A heating unit comprising a fluid tight hollow panel having an opening therethrough adjacent the top, an interior wall defining within one hollow end of the panel a supply column extending from the base of the panel to the top level of said opening, said structure affording a top cross-flow channel in the panel communicating with the top of the supply column, said panel having a vertical flow channel communicating with the opposite end of said cross-flow channel and disposed at the side of said panel opposite said supply column, a baffle in the hollow panel beneath said vertical flow channel for directing a flow of fluid transversely across the panel beneath the said opening, said panel formed with a cross-flow channel beneath the opening for receiving the said cross-flow from the baffle and being further provided at the base thereof with still another cross-flow channel, said panel intermediate the last mentioned two cross-flow channels being formed into a series of vertical passages connecting the said two cross-flow channels, and hollow horizontal grill-forming members traversing the said opening and communicating at opposite ends with the supply column and said vertical flow channel.

8. A space heating device comprising a hollow panel having a self-contained vertical supply column, a horizontal supply header traversing the column and in uncontrolled communication therewith, hollow convactor units arranged behind the panel in spaced relation and communicating at their tops with said supply header, an adjustable orificing tube rotatable in the header controlling supply to the convactor units independently of the radiator, and a return header connecting with the bottom of said panel and said convactor units.
